UNITED STATES PATENT OFFICE

HENRY G. FILLER AND HERBERT C. FILLER, OF ST. PETER, MINNESOTA

RAILROAD TIE

Application filed July 3, 1929. Serial No. 375,760.

The present invention appertains to new and useful improvements in railroad surface trackage and more particularly to a novel tie structure.

5 The improved tie structure includes a novel means whereby the rails may be securely fastened thereto, with the end in view to permit rails to be quickly detached from the ties for the purpose of replacement or when a new 10 road is being laid to facilitate the securing of the rails to the ties.

The principal object of the invention is to provide an improved tie structure to which rails may be secured in a much quicker manner than is possible by the use of wooden ties and securing means in the form of spikes.

Another important object of the invention is to provide a tie structure which will be practically indestructible and immune to the 20 usual conditions which deteriorate wooden ties.

These and other important objects of the invention will become more apparent to the reader after considering the invention as described and claimed hereinafter.

In the drawings:

Figure 1 represents a top plan view of the novel tie, showing rails secured thereto.

Figure 2 represents a side elevation of the 30 improved tie and a partial longitudinal section.

Figure 3 represents a vertical transverse sectional view through the improved tie.

Figure 4 represents a top plan view of the 35 supporting plate for each rail.

Figure 5 represents an edge elevation of the supporting plate.

Figure 6 represents a perspective view of one of the keys for securing the inside fasteners.

Figure 7 represents a fragmentary side elevation of a tie provided with a slightly modified form of fastener.

Figure 8 represents a fragmentary top 45 plan view of the tie with the fasteners removed, to show the manner in which the same is slotted.

Figure 9 represents a fragmentary side elevation of a modified form of tie.

50 Figure 10 represents an end elevation of

the supporting block for use in connection with the modification shown in Figure 9.

Referring to the drawings wherein like numerals designate like parts, it will be seen that the improved tie consists of an elongated block 5, of concrete, preferably having the upwardly converging side surfaces 6.

An elongated plate 7 is superimposed upon the tie 5 and extends from end to end thereon. The longitudinal edge portions of this plate 60 are bent downwardly as at 8 and these bent down edge portions have their outer surfaces flush with the sides 6-6 of the tie 5. The plate 7 is also provided with a flange 9, depending therefrom and having its longitudinal edge portions embedded in the tie 5 as clearly shown in Figure 3.

As is clearly shown in Figure 8, at each side of the approximate position where the rail traverses the tie plate 7, outside and inside cut-outs 10 and 11 are provided. The cut-out 10 consists in the provision of a pair of elongated slots 12-12 each of which has a pair of notches 13 extending toward the notches projecting from its complementary slot 12. The cut-out 11 is formed by a pair of elongated slots 14, which also have notches 15 extending toward each other, in the manner as clearly shown in Figure 8.

Outside and inside securing plates, generally referred to by numerals 16 and 17 respectively are each provided with tongues 18, for disposition within the notches of their respective cut-outs 10 or 11. It will be seen that the plate 16 is first adjusted in position 80 against the rail base with its upwardly disposed portion 19 engaging over the edge portion of the rail base, after which the rail is forced against the same, and the securing plate 17 adjusted in position.

After placing the plate 17 in proper position with its upwardly disposed end portion 20 disposed against the edge portion of the rail base, key members 21 are engaged within the slots 14 and between the inner end of the slot and certain tongues 18, so as to prevent the inward movement of the securing plate 17 after having been once engaged against the rail base. Each of these keys 21 consists in construction of a single piece of material 90

formed at one end with a notch 22, to engage the edge portion of the plate 7 at the corresponding end of the slot 14, in which it is seated, while the opposite end of the plate is provided with an aperture 23, into which a hook or other implement may be engaged for removing the key when desired. The keys 21 are to rest upon the pin 21' which passes through the flange 9 and serves as a rest for the key to maintain the key with its longitudinal axis underlying the plate 7. The securing plate 16 as well as the plate 17 is provided with a reinforcing rib 24 at its top side.

In Figure 7, the same character of fastener 15 is employed for the rails, excepting that the supporting plate 25 is interposed between the base of the rail and the plate 7. The supporting plate is further shown in Figure 4 and consists of a rectangular piece of metal, provided at diametrically opposite corners with upstanding members 26, extended inwardly at their end portions 27 for disposition over the opposite edge portions of the rail base.

In this form of the invention, a shim 28 may be interposed between the rail base and the supporting plate 25 and struck out prongs or spurs 29 on the plate will bite into the shim to prevent displacement thereof.

In Figure 9, another form of the invention 30 is shown wherein the upstanding members 26 are relatively longer than in the form shown in Figure 7 and also have their end portions turned inwardly for disposition over the rail base.

35 However, in this form of the invention, a thicker block 28' is employed and this block is provided with notches 29 at its under side. The end portions 19 and 20 of the fasteners 16 and 17 respectively, instead of being disposed upwardly for engaging the slotted surfaces of the rail face are disposed on the same plane with the balance of their structures for disposition within the notches 29 of the block 28' for engagement over the supporting plate 25 in the manner clearly shown in Figure 9.

40 It will thus be seen that the present invention presents a novel tie structure for supporting and maintaining in proper position the rails of a railway track way and although the present invention has been hereinbefore described in definite terms, it is to be understood that numerous changes in the specific shape, size and materials may be restored to, without departing from the spirit or scope 45 of the invention.

50 What is claimed is:

55 In combination, a tie having an abutment thereon for each track rail, said tie being provided with slots adjacent each abutment, a 60 fastener for each rail, said fastener means comprising a plate having a rail engaging lip at one end, the opposite end of the plate being notched, a lug on the plate for engagement in the slot, and a pivotally mounted key member engageable within said notch for inter-

position between the plate and the tie and at one end of the corresponding slot, and being adapted for actuation to push the plate against the rail so that the same is centrally clamped between the adjacent abutment and the lip of the said plate, said key being provided with a notch at its free end.

70 In testimony whereof we affix our signatures.

HENRY G. FILLER.
HERBERT C. FILLER.
